UNITED STATES PATENT OFFICE.

ROBERT HENEAGE, OF BUFFALO, NEW YORK.

IMPROVEMENT IN TOBACCO-SMOKING PIPES.

Specification forming part of Letters Patent No. 36,092, dated August 5, 1862.

To all whom it may concern:

Be it known that I, ROBERT HENEAGE, of the city of Buffalo, county of Erie, and State of New York, have invented a new and Improved Tobacco-Pipe; and I do hereby declare that the following is a full, clear, and exact description of the construction and operation of the same, reference being had to the accompanying drawings, and the letters of reference marked thereon, in which—

Figure I is a side elevation of my improved pipe, and Fig. II is a longitudinal section of the same.

Like letters refer to like parts in both figures.

A is the pipe-bowl, having an upward and forward projection from its bottom, through which is made the draft-hole b, and also a neck, C, projecting from the upper back corner, into which the stem D is inserted. The opening in the bowl at the top is closed tight by a plug or cover, e.

f is a chamber formed beneath the neck C on the back of the side of the bowl, and communicating with the passage through the neck and stem, and having a plug, g, at the bottom.

The pipe-bowl is filled with tobacco from the top, and the opening is then tightly closed by the cover e, so that no air can enter from the top. The tobacco is lighted at its bottom through the draft-hole b, and as this draft-hole is the only opening through which air can enter the pipe, and the suction being at the

upper part and above the tobacco in the bowl the draft will be up through the tobacco, in stead of down through it, as in the common pipe in use. There are several advantages gained in thus causing the draft to pass up through the tobacco. The oil which is formed from the tobacco by the heat falls upon the burning tobacco and is entirely consumed, so that there is no possible chance for it to be drawn through the stem into the mouth of the smoker. Again, the tobacco being lighted at the bottom as it burns away, may be replenished from the top without requiring relighting. The chamber f is filled with cotton or other suitable material, which catches and absorbs the saliva which always enters the stem from the mouth of the smoker and runs down upon the tobacco. The cotton will also prevent ashes, or cinders, or fine particles of tobacco being drawn into and through the stem. Clean cotton may be inserted as often as necessary by removing the plug g.

I claim—

In tobacco-pipes, placing the opening at which the tobacco is ignited at or near the bottom of the bowl, and closing the top of the bowl with a tight cover, the whole constructed substantially as described.

ROBT. HENEAGE.
